UNITED STATES PATENT OFFICE.

JOSEPH ELSWORTH, OF WELLSBOROUGH, PENNSYLVANIA.

DESIGN FOR A KITCHEN-CABINET.

SPECIFICATION forming part of Design No. 23,613, dated August 29, 1891.

Application filed April 9, 1894. Serial No. 506,957. Term of patent 3½ years.

To all whom it may concern:

Be it known that I, JOSEPH ELSWORTH, a citizen of the United States, residing at Wellsborough, in the county of Tioga and State of Pennsylvania, have invented a new and original Design for Kitchen-Cabinets; and I do hereby declare the following to be a full, clear, and exact description of the invention, such as will enable others skilled in the art to which it appertains to make and use the same.

My invention relates to a new and original design for kitchen cabinets and the like, and has for its object to provide a cabinet that shall be ornamental and attractive.

15 The essential feature of my design resides in a base or lower portion substantially rectangular in shape, provided with an upper portion of about half the depth of said base and having the cornice P and ornamental top Q.
20 The base or lower portion presents to the eye four general upright divisions, of equal width, and the upper portion three such general divisions.

In the drawing, A is the base or lower portion and B the upper portion. The lower 25 portion has vertical panels, L, and horizontal panels K, end-leaves C and legs D. The upper portion has a row of horizontal panels, M, and vertical panels, O. P is the cornice and Q the top. All the elements, it will be 30 noted, are grouped in such a way as to produce a very attractive and ornamental cabinet.

Having thus described my newly-invented design, what I claim, and desire to secure by 35 Letters Patent, is—

The design for a kitchen cabinet or the like substantially as shown and described.

In testimony whereof I affix my signature in presence of two witnesses.

JOSEPH ELSWORTH.
